S. E. CHUBBUCK, OF ROXBURY, MASSACHUSETTS, ASSIGNOR TO JOSEPH H. CHADWICK, OF SAME PLACE.

Letters Patent No. 67,721, dated August 13, 1867.

IMPROVED APPARATUS FOR MOULDING PLATES OF LEAD.

The Schedule referred to in these Letters Patent and making part of the same.

TO ALL WHOM IT MAY CONCERN:

Be it known that I, S. E. CHUBBUCK, of Roxbury, in the county of Norfolk, and State of Massachusetts, have invented a new and useful improvement in the Process of Manufacturing Sheet Lead; and I do hereby declare that the following is a full, clear, and exact description thereof, which will enable others skilled in the art to make and use the same, reference being had to the accompanying drawings, forming part of this specification.

Sheet lead is now most generally produced by milling or rolling lead plates of considerable thickness down to a quite thin sheet, the plate being passed back and forth between pressure-rollers until it is compressed and drawn out or reduced down to the required thickness. The plates are formed by melting a requisite amount of pig lead, and pouring the same into a cast-iron box or mould, the dimensions of which, internally, correspond to the desired size of the plate to be milled or rolled. Considerable difficulty has hitherto been experienced in casting these plates, in consequence of the mould or box chilling the melted lead as it is poured into it, and causing the plate to have folds or seams extending wholly or partially through it, which greatly deteriorate the milled or rolled lead, as the folds or seams do not unite under pressure, and the rolled lead frequently parts or separates, and sometimes will have holes in it.

My invention is designed to obviate this difficulty; and to this end it consists in constructing the box or mould with a steam-chamber, so arranged that the former may be heated to a proper temperature, in order that the melted lead, when poured into it, will not chill rapidly, or before the box or mould is filled, and thereby admit of the whole mass in the box or mould cooling and forming a compact mass or plate.

My invention also consists in suspending the box or mould on pivots, and applying gearing to the same, in such a manner that the box or mould, with the plate it contains, may be readily inverted, and the plate discharged with the greatest facility. In the accompanying sheet of drawings—

Figure 1 is a vertical section of my invention, taken in the line $x x$, fig. 2.

Figure 2, a vertical section of the same, taken in the line $y y$, fig. 1.

Similar letters of reference indicate like parts.

A A represent strong uprights, resting upon a suitable base, B, and having a box or mould, C, suspended between them by journals $a a'$, the latter being allowed to turn freely in the uprights. This box or mould is of rectangular form, and of a capacity requisite to admit of a plate of lead being cast of the required dimensions. Underneath the box or mould there is a chamber, D, into which steam is admitted through one of the journals a , both journals being hollow or tubular, the steam escaping through the other journal a' . The latter may be closed by a safety-valve, if necessary or desired. This steam-chamber keeps the box or mould C in a warm state, and effectually prevents the melted lead, when poured into C, from cooling before the same is filled. On the journal a there is keyed a toothed wheel, E, into which a pinion, F, gears, the latter having a tubular shaft, b, which is fitted on an arm, c, attached to or projecting from one of the uprights A, the shaft b having a crank, G, attached to it, for the convenience of turning it.

By this means the box or mould, when filled, may be readily inverted, and the casting discharged from it upon a carriage placed underneath to receive it. The box or mould, while being filled with the melted lead, is supported in a horizontal position by jacks placed one under each corner. These jacks are of course removed when the box or mould is to be inverted.

I do not claim the suspending of the box or mould on pivots, for that has previously been done for the convenience of inverting it to discharge the casting; but the gearing, so far as I am aware, has not been used to aid the operation; neither do I claim broadly the heating of metal moulds; but, having thus described my invention, what I claim therefore as new, and desire to secure by Letters Patent, is—

The improved machine herein described, for the purpose set forth.

S. E. CHUBBUCK.
